PAUL ECKARD,

INVENTOR.

BY *Arthur D. Ringer,*

HIS ATTORNEY.

UNITED STATES PATENT OFFICE

2,192,639

HOSE SPRINKLING NOZZLE

Paul Eckard, Los Angeles, Calif.

Application June 8, 1938, Serial No. 212,497

1 Claim. (Cl. 299—146)

This invention relates to devices commonly applied to, and used with, watering hoses.

One of the objects of this invention is to provide a sprinkler with quick-changing means between a wider spray and a central single stream discharge.

Another object is to provide joint adjusting means for the wider spray and the central discharge.

Another object is to provide separate adjustment for the central single stream discharge.

Another object is to provide means for easily assembling and disassembling the device.

Another object is to provide means for exchangeably holding the front apertured cap.

Other objects will appear from the following description and appended claim as well as from the accompanying drawing, in which—

Fig. 1 is a side elevation of the assembled sprinkler nozzle.

Fig. 2 is a longitudinal midsectional view of the nozzle, open for the central discharge.

Fig. 3 is a cross section on line 3—3 of Fig. 1.

Fig. 4 is a cross section on line 4—4 of Fig. 2.

Fig. 5 is a longitudinal midsectional view of a slightly modified form of nozzle.

Fig. 6 is a fragmentary plan view of the housing.

Fig. 7 is a side view of the housing portion of Fig. 6 as seen in the direction of the arrow 7.

Fig. 8 is a fragmentary rear view of the removable clamping ring.

Fig. 9 is a cross section on line 9—9 of Fig. 8.

As illustrated, the rear end of the sprinkler nozzle is formed to screw and fit on a hose, this portion being indicated at 10.

This portion 10 is provided with a cup-shaped extension 11, which is provided with distinct openings 12 and 13, one for feeding the wider spray, and another for feeding the central single stream discharge.

The sprinkler head is adjustably and turnably mounted on the cup-shaped extension 11 and consisting of an outer housing 14, an inner sleeve 15, and an intermediate partition 16, all being firmly united so as to turn together on the cup-shaped extension 11.

In other words, when the outer housing 14 is turned, the inner sleeve 15 is also turned.

This united structure is provided with distinct openings for separately forming communications with the inside of the cup-shaped extension 11; for one thing, to feed by way of the opening 13 and through one of these additional openings, in this case being the opening 17 in the inner sleeve

15, to form the communication between the inside of the cup-shaped extension 11 and the space formed by the inner sleeve 15 and the partition 16, whereby any water may reach the central single stream discharge; and, for another thing, to feed by way of the opening 12 and through another of these additional openings, in this case being the opening 18, jointly in the inner sleeve 15 and the partition 16, to form the communication between the inside of the cup-shaped extension 11 and the space formed by the partition and the outer housing 14, whereby any water may reach the wider spray cap 19 when the united structure is turned so that the opening 18 comes into alignment with the opening 12, as is the case in the modified form of Fig. 5.

From comparing Figs. 2 and 5 it is evident that a turning of the united structure upon the cup-shaped extension in one direction gives a clear communication for the central single spray; while, a turning in the opposite direction gives a clear communication for the wider outer spray.

While the head is turned for the central single discharge, this may still be adjusted for a larger or less amount by means of the adjusting sleeve 20, of which the innermost end 21 may be made to seat tightly upon the washer 22, so that, by a very fine opening, a fine spray may even be had through the central discharge, though, by a full opening of this sleeve 20, a larger rather solid stream may be had, which may be useful in hosing off a sidewalk or similar surface.

The whole united structure of outer housing 14, inner sleeve 15, partition 16, cap 19, and adjusting sleeve 20, are firmly, though turnably, held to the cup-shaped extension 11 by means of the screw-pin 23.

The cap 19 may be crimped directly to and over the edge of the housing 14 though a separate clamping ring 24 has been indicated.

This clamping ring may even be shaped so as to facilitate an exchanging of caps with different, larger or smaller apertured, spraying means.

Such a possibility is more specifically detailed in Figs. 6, 7, 8, and 9.

The edge of the housing would in such a case preferably be provided with notches indicated at 25 in Fig. 6, though, of course, such notches may be longer, shorter, rounded, squarely cut, triangular cut, or similarly slightly modified without materially changing anything on the principle.

Each of the projections, or outwardly extending edge portions 26, are preferably shaped to form

wedge-like means when seen from the side, as illustrated in Fig. 7.

The clamping ring, suitable for such an edge, takes eventually the form illustrated in Figs. 8 and 9; while the outer edge may preferably be in form of a smooth flange 27 the opposite edge would naturally have to have notches to correspond with the notches in the edge of the housing 14 and also wedge-like as indicated at 28 in Fig. 9.

To assure a quick and positive proper location of the turning position of the housing on the cup-shaped extension, stops are provided on the rear base portion 10 as well as on the housing, or united structure, as indicated in Fig. 3, one stop 29 being on one part, while the other stop 30 is on the other part, whereby the housing may be quickly and positively brought to aligning position for discharging through either the wider spray or the central single stream discharge; though, of course, the previously referred to communications may be opened more or less without turning to the full-discharge stop positions.

The cup-shaped extension is not necessarily of the cylindrical form illustrated in Fig. 2, as will be understood from the illustration in Fig. 5, in which this extension 11a is conical, and the

sleeve portion 15a, of course, correspondingly shaped.

From the above, and from the illustrations, it should be understood that any discharge from a connected hose can be shut off entirely by reason of the fact that the openings 17 and 18 can be far enough apart that neither will be in aligning position.

Having thus described my invention, I claim:

In a hose sprinklerhead of the type described, a base having a portion to screw to the end of a hose and having a cup-shaped extension with distinct discharge openings, a head having a portion to turnably fit on said extension with an outer housing and a partition between the housing and the portion forming distinct compartments, a wide-spray cap over the outer compartment, a central narrow-spray means in operative relation to the inner compartment, adjusting means for the narrow-spray means whereby the narrow spray may be adjusted between a single-stream full discharge and a fine spray, and the head having distinct communicating openings for the compartments to individually align with the openings in the extension.

PAUL ECKARD.
